UNITED STATES PATENT OFFICE

156,449

TIE KNOT ORNAMENT

Louis C. Marchetti, St. Paul, Minn.

Application August 22, 1949, Serial No. 4,642

Term of patent 7 years

(Cl. D45—19)

To all whom it may concern:

Be it known that I, Louis C. Marchetti, a citizen of the United States, residing at St. Paul, in the county of Ramsey and State of Minnesota, have invented a new, original, and ornamental Design for a Tie Knot Ornament, of which the following is a specification, reference being had to the accompanying drawing, forming part thereof.

I claim:

The ornamental design for a tie knot ornament, as shown.

LOUIS C. MARCHETTI.
